UNITED STATES PATENT OFFICE.

JOHN HANCQ, OF JAMESTOWN, NEW YORK.

ELECTRIC WARP STOP-MOTION.

1,180,144.

Specification of Letters Patent. Patented Apr. 18, 1916.

Application filed March 27, 1915. Serial No. 17,355.

To all whom it may concern:

Be it known that I, JOHN HANCQ, a citizen of the United States, residing at the city of Jamestown, in the county of Chautauqua and State of New York, have invented certain new and useful Improvements in Electric Warp Stop-Motions, of which the following, taken in connection with the accompanying drawings, is a specification.

The invention relates to electric warp controlling devices for looms and is an improvement on the warp stop motion shown in my Letters Patent Nos. 1,065,938, July 1st, 1913, and 1,071,313, August 26, 1913; and the object of the present improvement is to provide a heddle frame having improved channel flanges lengthwise of the inner edges of the top and bottom rails providing a simply constructed hooked heddle and means for admitting said hooked heddle to said channel flanges and also to provide a novel electric circuit breaker to make and break the electric circuit as the heddle frame rises and falls, and also to connect said heddle mechanism with an electric knock-off for the loom; and the invention consists of the novel features and combinations hereinafter set forth and claimed. The stopping mechanism proper shown in Figs. 1, 8, 9, 10 and 11 and described herein is claimed in my companion application Serial No. 17,356 filed March 27, 1915.

In the drawings, Figure 1 is an end elevation of the loom with the electric warp stop motion and knock-off mechanism attached thereto, a portion of the end frame being broken away to show the position of the parts. Fig. 2 is an elevation of the heddle frame with the heddles in position, certain portions being broken away to shorten the frame and showing the electrical connection whereby the electric circuit is alternately made and broken with the rise and fall of the heddle frame in the loom. Fig. 3 is a sectional view of the frame at line X X in Fig. 2 showing the heddle as it is normally supported with unbroken threads, the heddle frame being at the lowest point of its travel; and Fig. 4 is a similar view with the thread broken and the electrical circuit closed by the heddle resting upon an electrically charged bar on the upper cross rail of the frame. Fig. 5 is a lengthwise sectional view of the circuit breaker or make and break bar of the electrical connection

supporting the heddle frame showing in detail the construction of the same. Fig. 6 is a perspective view of the end of the lower hooked flange and its attachment to the end of the frame whereby a gate is formed for the admission of the heddles; and Fig. 7 is an elevation of the latch or gate bar. Fig. 8 is an elevation of the electrical knock-off mechanism for operating the stopping mechanism of the loom, the tripping mechanism being shown in normal position with unbroken threads; and Fig. 9 is a similar view showing the tripping action of the magnet in operating the stopping mechanism of the loom when a thread breaks; and Fig. 10 is a sectional view at line Y Y in Fig. 8 showing a top plan view of the tripping mechanism and return actuating coil springs. Fig. 11 is a perspective view of the lower tripping plate, a portion of the plate being broken away to show the magnet operated tripping dog by means of which the stopping mechanism is actuated when a thread breaks.

Like numerals of reference refer to corresponding parts in the several views.

The numeral 10 designates the loom upon which the heddle frame 11 is supported by means of a strap 12 which passes over the rolls 13, one of the straps 12 being joined to the other and the single strap passing around additional rolls to the bottom roll 14 and then passing to the hooks 15 in the lower edge of the heddle frame 11.

The heddle frame 11 comprises the top cross rail 16 and bottom rail 17 and connecting end pieces 18. The heddle frame 11 is preferably made of wood or some other equally good insulating material. The top and bottom cross rails 16 and 17 have the sheet metal single hook flanges 19 and 20 inset lengthwise in their opposite inner edges. Said opposite inner edges 21 and 22 are formed at opposite angles and the hooked lengthwise flanges have a turned lengthwise shoulder at the same angle so as to brace firmly against the beveled surface of the wood frame and extending out preferably to about the edge of the same and then continuing inward in the required hook. This arrangement provides a self-cleaning opening for the lower flange, since all lint and dust will fall out of the same as the frames pass up and down and are thereby shaken. All that is necessary also to clean the upper hooked flange 19 is to turn the frame 11 up-

side down and shake it, the bevel of the frame permitting the free exit of all lint and dirt, thus aiding greatly in providing clean contact surfaces for the heddles. The two flanges 19 and 20 are connected about midway of their length by a cross bar 23 which renders the entire frame much more rigid yet is so placed as to be out of the way of the heddles as they slip back and forth upon the flanges 19 and 20.

The heddle 24 is composed of a thin sheet steel strip having oppositely hooked ends 25 and 26 which fit around the hooked flanges 19 and 20 so as to allow a sufficient amount of play to make and break contact with the top flange 19. A thread eye 27 is provided about midway of the length of the heddle formed by a lengthwise cut and the opposite portions of the strip being bent in opposite directions so that as the heddle stands edgewise toward the direction from which the thread extends an eye is easily formed by sidewise bends and the entire heddle may be struck out by means of suitable dies.

The upper flange 19 is provided with a contact strip 28. The edge of the flange is given a double return bend to form a second groove 29 within which the contact strip 28 is embedded in insulation so as to completely disconnect the strip 28 from the flange 19. This simple construction permits its formation by means of suitable dies and holds the contact strip 28 in the exact position desired for contacting the heddles 24. The lower flange 20 is preferably turned upon itself to form a closed tubular opening 30. The turning of the edge to form a tube 30 forms a rounded surface which is easy to slip the heddle 24 upon. In order to enter the heddles, a gate or latch is provided at one end of the flange 20 which is shortened to provide a space 31 between the end of the flange 20 and the frame end piece 18. A slot is provided through the end piece 18 through which a latch piece 32 is inserted which latch piece has an open ended slot 33 providing a small tongue 34 which is insertible in the tubular opening 30 in the end 50 of the flange 20. A spring latch 35 is provided on the outer edge of the end piece 18, the turned end of which inserts through a hole 36 in the latch piece 32 when the latch piece is in place, thereby securing said latch piece in place and preventing the escape of any of the heddles while the frames are traveling upward and downward in the loom.

Separate electrical connection is made to the end of the bar 28 and to the flange 19 in the following manner: A supporting hook 37 is provided in the upper cross bar 16 of the heddle frame which abuts against the upper edge of the flange 19, thereby making an electrical contact on the same, while the

supporting hook 38 for the opposite end of the heddle frame does not contact with the flange 19 but is connected by means of a wire 39 to the end contact bar 28.

In order to make and break the electrical connection as the heddle frame rises and falls in the loom, a spring contact bar 40 is attached to each of the supporting hooks 37 and 38 at one end and to the straps 12 at the other. The contact bars 40 each comprises a bar of insulating material with a lengthwise opening therethrough to receive the channel shaped sheet metal strip 41. The hooks 37 and 38 are inserted through holes in strip 41 at the lower end. At the upper end of each a hook 42 is pivotally secured for attaching to the strap 12. A spring contact wire 43 is attached within the channel strip 41 by coiling around a post 44 at one side. This gives the lower end 45 of the contact wire 43 a spring pressure on the end of the hook 37 or 38 holding said hook firmly in the channel strip 41 and providing a constant contact therewith. The end 46 of the contact wire 43 extends out through a slot 90 in the side of the bar 40 and thence inwardly at right angles to engage against a stopping post 47 with spring pressure. A pair of pins 48 are supported on a downwardly projecting bar 49 on the loom frame 10 to 95 provide a pin 48 each side of each of the contact bars 40, as shown in Fig. 2, so that as the heddle frame passes down in the loom the outwardly bent portion of the contact wire 43 will be pressed into firm contact with one of the pins 48 and will continue in contact until the heddle frame passes up and the contact wires 43 are drawn out of touch with the pins 48.

The electrical connection consists of a 105 wire 50 to the pins 48 of the contact bar 40 engaging the hook 37, the wire 50 leading to a battery 52. A second wire 51 connects to the pins 48 each side of the contact bar 40 attached to the hook 38, which hook is 110 connected by wire to the contact bar 28.

It is apparent that as the heddle frames pass up and down the heddles 24 will be drawn up out of contact when the frame is in the lowered position but when in the 115 raised position the heddles 24 will drop upon the contact bar 28. It is accordingly necessary that when in the raised position said contact bar should be disconnected, that is, the circuit should be broken. This 120 is accomplished by means of the contact bars 40, for it is apparent that when in the raised position, as shown in Fig. 2, the current is entirely disconnected. When in the lowered position, as shown in Fig. 3 the 125 parts are in electrical contact but the heddle is raised thereby breaking the circuit so that when the thread 53 breaks, the heddle 24 drops onto the contact bar 28 thereby completing the circuit to stop the loom.

In order to effectively operate the stopping mechanism of the loom an electrical knock-off mechanism is necessary. For this purpose I prefer my knock-off mechanism as shown in Figs. 8, 9, 10 and 11, which knock-off mechanism is included in the electrical circuit as shown in Fig. 1, by the connecting wires 50 and 51. Usually the loom has a lever or crank 54 which is attached to the end of the break rod 55. The end of the lever 56 is extended to engage in the upturned end 57 of the slidably mounted tripping bar 58. The tripping bar 58 is supported by slidably extending through a box 59. A second tripping bar 60 is slidably mounted in the box 59 and extends therethrough over the bar 58 so as to slidably rest thereon. The bar 60 is connected by a pitman 61 to a crank wheel 62 on the driving shaft 63 of the loom, so that when said shaft 63 is located the tripping bar 60 is reciprocally moved backward and forward on the tripping bar 58. A wire 64 connects the battery 52 to a spring 65 on a post 66 in the box 59 which has a spring end 67 which extends up to a contact plate 68. The contact plate 68 is connected by wire to a magnet 69 supported in the box 59 below the tripping bar 58. Insulated pins 70 and 71 are provided on bars 58 and 60 to engage the spring end 67 of the contact wire, the pin 71 moving the spring end 67 away from the contact plate 68 and then permitting it to spring back against the same. A pin 72 is provided in the box 59 to support a coil spring 73 which engages a pin 74 on the tripping bar 58 to normally hold said tripping bar with the pin 70 firmly pressed against the inner wall of the box 59 and at the same time to hold the lever 54 in its normal position when the loom is running with unbroken threads, as shown in Fig. 1. A dog 75 is pivotally attached in a slot 76 in the tripping bar 58 near one end of said box so that the long end thereof normally rests upon the wall of the end of the slot 76, so that said dog 75 is normally out of the way of the reciprocating bar 60 as it moves backward and forward making and breaking contact. The bar 60 has a notch 77 cut in the underside thereof to receive the long end of the dog 75. The short end of the dog 75 is made broad and flat and extends beneath the bar 58 to provide a contacting surface a spaced distance from the top contact plate of the magnet 69 which magnet is connected to the contact plate 68, the contact wire 67 being made to make contact when the heddle frames are at the upper or lower limit of their travel, and to break contact when the frames are moving either upward or downward. The knock-off contact breaker is necessary to make and break contact with greater rapidity than would be possible

with the contact bars 40. When the thread breaks and the electrical circuit is closed, the magnet 69 is instantly charged thereby drawing down upon the short end of the dog 75 and turning the long end of the dog 70 upward into the path of the notch 77 in the lower side of the reciprocating bar 60. The movement of the bar 60 is thereby communicated to the bar 58 pushing out said bar 58 and operating the lever 54 and the stopping mechanism for the loom attached thereto thereby almost instantly stopping the loom.

I claim as new:

1. In a device of the class described, a heddle frame comprising upper and lower cross bars and connective end pieces, the inner edges of said cross bars oppositely beveled, lengthwise hooked flanges inserted in the beveled inner edges of said upper and lower cross bars and extending a spaced distance at the same angle as said beveled edges to brace and clear said hooked flanges of dirt, heddles having hooked ends to engage over said hooked flanges, the central portions of said hooked flanges connected out of line with said heddles, a contact strip on the upper hooked flange and insulated therefrom to receive the hooked end of said heddle, said hooked flange and said contact strip having separate connections to the source of electrical energy.

2. In a device of the class described, a heddle frame comprising upper and lower cross bars and connective end pieces, lengthwise hooked flanges on the inner edges of said upper and lower cross bars having their inner edges in a lengthwise return bend, a second lengthwise return bend on said inner edge of said upper hooked flange, a lengthwise contact strip inserted within said second return bend and insulated and projecting upwardly therefrom, said upper flange and contact strip having separate connections to the source of electrical energy, and heddles having hooked ends to engage over said hooked flanges to drop onto said contact strip when the thread breaks.

3. In a device of the class described, a heddle frame comprising upper and lower cross bars and connective end pieces, lengthwise hooked flanges inserted in the inner edges of said upper and lower cross bars, heddles having hooked ends to engage over said hooked flanges, a contact strip on said upper hooked flange insulated and projecting upwardly therefrom to receive the hooked end of said heddle, said contact strip and said hooked flange having separate connection to the source of electrical energy, the inner edge of said lower hooked flange turned on itself to form a tube, the end of said lower flange a spaced distance from one of said connective end pieces to permit the insertion of said heddles onto said flanges, a locking plate inserted through said end

piece into said edge tube, and a latch to hold said locking plate in position.

4. In a device of the class described, a heddle frame comprising upper and lower cross bars and connective end pieces, lengthwise hooked flanges on the inner edges of said upper and lower cross bars, heddles having hooked ends engaging over said hooked flanges, a contact strip on said upper hooked flange insulated therefrom and projecting upwardly to receive the hooked end of said heddle, said hooked flange and said contact strip having separate connections to the source of electrical energy consisting of spaced contact pins on the loom and electrical connection to said pins, and supporting bars for said heddle frame between said pins and spring contact wires within said supporting bars to make and break contact with said pins.

5. In a device of the class described, a heddle frame, hooked flanges on the opposite inner edges of said frame, heddles having hooked ends to engage over said hooked

flanges, a contact strip on the upper hooked flange insulated therefrom, separate connections to the source of electrical energy for said upper hooked flange and said contact strip consisting of supporting hooks for said heddle frame, supporting bars attached to said supporting hooks and spring contact wires extending out from the upper portion of said supporting bars, spaced contact pins on the loom frame each side of said supporting bars to make and break contact with said spring contact wires as said supporting bars pass up and down between said spaced contact pins, in combination with electrical knock-off mechanism for the loom, and electrical connection between said pairs of pins and said knock-off mechanism and the source of electrical energy.

In testimony whereof I have affixed my signature in the presence of two witnesses.

JOHN HANCQ.
